KEYLESS DOOR LOCK

Leonard Courtney Mook, Jr., Lancaster, Pa.

Application September 8, 1938, Serial No. 228,996

6 Claims. (Cl. 292—169)

My invention relates to an improvement in keyless door locks.

An object of my invention is to provide a keyless door lock which may be locked from one side 5 of the door and which may not be unlocked from the other side of the door except in emergencies.

A further object of my invention is to provide a keyless door lock which may be readily locked when desired from one side of the door, but 10 which will not become locked inadvertently or by accident.

A further object of my invention is to provide a keyless door lock which is both reversible and invertible so that it may be applied to doors 15 which are either right-hand or left-hand and may be adjusted so that it can be locked from either side of the door.

A still further object of my invention is to provide a keyless door lock which is relatively thin 20 and may be used as a mortise lock even on thin doors, such, for example, as on screen doors.

My keyless door lock is designed to be used principally as a lock for a bathroom door, a screen door, a door to a photographic dark 25 room, or a door to any other room in which the occupant wishes not to be disturbed.

In the accompanying drawing:

Fig. 1 is a side elevation with the lid removed, and

Fig. 2 is a horizontal cross-section showing the divided shafts disengaged from the lock.

The case for my lock is conventional in form; it is provided with a box-like casing 2, a face 35 plate 4, and a lid or cover plate 6 which is held in position on the casing 2 by customary screws 8.

Within the casing 2 I provide a latch bolt yoke 10 which has on its outer end a latch bolt 12. This latch bolt yoke 10 is forced outwardly 40 through the face plate 4 by the spring 14 which presses against the inside of the latch bolt 12 and the studs 16 which are made integral with, or may be secured to, the casing 2. The latch bolt yoke 10 at the end thereof remote from the latch 12 is provided with a pressure plate 18 45 against which the cam 20 and the locking cam 22 may be pressed to retract the latch bolt 12 at the time that the door is to be opened.

The yoke 10 is provided with pins 24 extending laterally therefrom and positioned approximately 50 half-way between the, latch bolt 12 and the pressure plate 18.

Between the pins 24 and the pressure plate 18 I provide a slot 26 in the yoke 10 so that the yoke may slide over the collars 28 of the cams 55 20 and 22. These collars 28 are provided with

square holes therethrough so that the divided shafts 30 and 32 may be properly engaged within the collars so that the cams may be turned when desired.

The locking cam 22 is provided with a slot, 5 which has on one side thereof a protrusion 34, and on the other side thereof a beveled edge 36.

When it is desired to lock the door, which can be done only from the inside, a conventional handle secured to divided shaft 32 is turned in 10 a counterclockwise direction with sufficient force so that the protrusion 34 is forced past the pin 24 extending laterally from the yoke 10. When the locking cam 22 is in this position, with the pin 24 engaged within the slot in the locking cam 15 and held there by the protrusions 34, it will be impossible to pull the latch bolt 12 inwardly, by turning the outside knob and the divided shaft 30, more than a slight distance, the distance between pin 24 and the other edge of the slot 20 within the locking cam 22.

Since the divided shafts 30 and 32 are screw-threaded together, the turning of the shaft 30 in one direction would merely loosen the screw-threads and consequently would not turn the 25 shaft 32 within the collar 28 of the locking cam 22. When in locked position, the turning of shaft 30 is prevented by the abutment of cam 20 against the pressure plate 18.

By providing the beveled edge 36 on the slot 30 in the locking cam 22, it will be impossible for the door to become locked from the outside because if the locking cam were thus moved toward its locking position the beveled edge 36 would come into contact with the pin 24, which would 35 be retracted with the latch bolt yoke 10 by the action of the cam 20, and tend to force the locking cam upwardly into a vertical or unlocked position.

In the event that the door should be locked 40 from the inside and for some reason, for example if it were locked by a child, the person inside were unable to unlock the door, it would be possible to unlock the door from the outside by merely removing the outside knob forcing the shaft 30 inwardly far enough to engage collar 28 of the locking cam 22 and then turning the shaft 30 in a counter-clockwise direction to disengage the protrusion 34 from the pin 24 and then to turn 45 cam 20 against the pressure plate 18 to retract the latch bolt 12 and unlock the door.

In order to accomplish this, it is necessary in assembling the lock to be certain that the square openings within the collars 28 be in alignment 50 55

at the time that the locking cam 22 is in a horizontal position, as is shown in Fig. 1.

To reverse the latch, all that is necessary is to turn the yoke 10 over. All parts can be reversed and turned over to suit purpose required.

Although I have shown one particular form of a yoke 10 and a locking cam 22, it will be understood that the exact configuration of these elements may be readily changed without departing from the spirit of the invention and the scope of the appended claims.

I claim:

1. A keyless door lock including a spring-pressed latch bolt yoke, a pressure plate on said yoke, a pin extending laterally from said yoke, and a locking cam adapted to engage said pin, the said locking cam including a slot having a protuberance extending from the side of said slot remote from said pressure plate.
2. A keyless door lock including a spring-pressed yoke, a latch bolt on one end thereof, a pressure plate on the other end thereof, a pin extending laterally therefrom approximately in the center thereof, a divided knob-shaft, cams on said divided shaft adapted to engage said pressure plate, and a locking slot in one of said cams positioned to receive the said laterally extending pin.
3. A keyless door lock including a latch bolt yoke, a latch bolt on one end of said yoke, a pressure plate on the other end thereof, a spring positioned to force the said latch bolt outwardly, a divided shaft passing laterally through an open-

ing in said yoke, and cams secured to said divided shaft in position to engage the said pressure plate, one of said cams being provided with a slot to receive and hold a pin extending laterally from said latch bolt yoke.

4. In a keyless door lock, a latch bolt yoke, a divided shaft passing laterally through an opening in said yoke, cams on the adjacent ends of the said divided shaft in position to engage a pressure plate on said yoke, and a slot in one of said cams in position to receive a pin extending laterally from said yoke, the said slot having on the side thereof, remote from the divided shaft, a protuberance to hold the said pin therein.

5. In a keyless door lock, a latch bolt yoke, a divided shaft extending laterally through said yoke, a cam on one end of said divided shaft in position to engage a pressure plate on said yoke, and a locking cam on the adjacent end of said divided shaft in position to engage said pressure plate, said locking cam having a slot therein positioned to receive a pin extending laterally from said yoke, the said slot having on the side remote from the divided shaft a protuberance and on the other side thereof a beveled edge.

6. A keyless door lock including a spring-pressed latch bolt yoke, a pressure plate on said yoke, a pin extending laterally from said yoke, and a locking cam adapted to engage said pin, the said locking cam including a slot having a beveled opening thereto.
